EXTENSION CIRCUIT SYSTEM

Louis M. Potts, Evanston, Ill., assignor to Teletype Corporation, Chicago, Ill., a corporation of Delaware

Application August 25, 1938, Serial No. 226,729

38 Claims. (CL 178—52)

This invention pertains to synchronous multiplex telegraph systems in which a channel of the system is equipped at its ends with signal receiving and translating devices connecting the channel operatively over further or extension line channels to remote substations. Specifically, the invention pertains to such systems in which the extension line channels may be single wire channels operated upon the two-way simplex system of start-stop telegraphy.

The object of the invention is to provide a simple and inexpensive mechanical means for translation of signals and for retransmission of translated signals from a first simplex line into a multiplex system and from the multiplex system into a second simplex line.

To effect the above result, mechanical devices are required in two classes, first an extensor having the functions of receiving start-stop permutation code signals from a substation at irregular intervals or at the maximum speed of which the substation is capable of storing the signals and of supplying the stored signals to a multiplex distributor commutator in such manner that the multiplex distributor may retransmit the stored code signals into a multiplex channel, and second, an extensor having the functions of receiving permutation code signals from said multiplex channel and retransmitting them in the form of start-stop code signals into an extension line channel.

Since each extension circuit of two-way simplex transmission nature must be connected to the first extensor for receiving code signals from the substation and to the second extensor for transmitting code signals to the substation, it is a further object of this invention to provide echo suppression signals preventing signals generated by the second extensor from regenerating any signals in the associated extensor.

It is a feature of this invention to provide a system of apparatus for transmitting a break signal through a multiplex channel by creating upon one simplex line a break signal of extended length and of spacing nature, translating the said break signal into a repeated permutation code signal, transmitting the repeated permutation code signal through the multiplex channel, receiving the repeated permutation code signal, and retranslating it into a break signal of extended length and of spacing nature upon a further simplex line.

It is a further feature of this invention to provide translating means for operating the above described method of transmitting a break signal,

and it is a still further object of this invention to embody the said break signal translating means mechanically in the structure of the respective extendors and to provide therein contacts for controlling signal lamps which will indicate a break signal or an accidental break in a line circuit, identifying at the same time the extension circuit in which the break has occurred.

The recited objects and features of invention 10 are attained by adding to a multiplex system, according to the present practice, only the required number of first and second extensor machines, with no modification of substation equipment upon the simplex lines and with a minimum modification of the distributing commutators within the multiplex system.

As illustrated in detail herein, a system of apparatus according to this invention comprises a multiplex line of a plurality of channels having 20 customary terminal apparatus of transmitting multiplex distributor and receiving multiplex distributor with which is combined, for each or for any channel, a pair of mechanical translating devices. One of the translating devices has 25 functions of receiving start-stop permutation code signals from a simplex line, storing the group of permutation elements of each code signal, and delivering the stored group of permutation elements to the transmitting multiplex 30 distributor in proper timing to effect transmission of the permutation group over a multiplex channel. The other of the pair of translating devices has functions of receiving the transmitted group of permutation elements from the 35 multiplex channel and immediately retransmitting the permutation group with added start and stop signals to form a complete start-stop permutation code signal upon a further simplex line.

In the first mentioned translating device, a 40 start-stop receiving distributor responsive to code signals received from a simplex line distributes the permutation impulses to a set of storage elements in which the permutation code remains stored until the transmitting multiplex 45 distributor reaches a signaling position, when a local signal from the transmitting distributor causes transfer of the stored combination to be impressed upon commutator segments for immediate transmission over the multiplex channel. 50 Three cam sleeves are provided on one motor driven shaft in this translating device, the first cam sleeve being responsive to a starting signal received from the start-stop simplex line and the second cam sleeve being started at conclusion of 55 the received code signal to qualify for operation

the retransmitting cam sleeve which is started in response to a starting signal from the transmitting distributor and which immediately transfers the stored code signal to segments of the multiplex distributor for transmission.

In the second mentioned translating device, a set of magnets and latches operate in response to received impulses to register a received code signal after which a local impulse from the receiving distributor to the translating device causes the registration to be transferred to a cam type start-stop distributor which immediately transmits a full start-stop code signal embodying the stored code signal to an extension simplex line.

Apparatus for transmitting the break signal as above described is embodied in part in the first mentioned translating device in the form of a means responsive to presence or absence of the stop impulse which normally follows a code combination of impulses in the simplex line. Upon opening a substation break key in the simplex line, the signal transmitted and received by the first mentioned translating device is equivalent to "blank" code signal repeated without any stop impulse. Absence of stop impulses causes the translating device to retransmit "figures shift" code signal repeatedly into the multiplex channel.

Further apparatus for transmitting the break signal is added to the second mentioned translating device in the form of a ratchet and driving pawl. The pawl responds to a received "figures shift" code signal to drive the ratchet step by step and after three or more steps, the ratchet operates a switch to open the extension simplex line, thus reproducing in the receiving extension circuit the breaking condition set up by the break key in the originating extension circuit.

A better understanding of the invention may be attained from the following description, taken in conjunction with the accompanying drawings, wherein

Fig. 1 illustrates a general circuit arrangement embodying the invention;

Fig. 2 illustrates, in a theoretical mechanical diagram, details of structure of an A extensor taken as of a vertical section through an axial plane of the power shaft of the extensor;

Fig. 3 illustrates the structure of an A extensor in theoretical mechanical diagram taken as at right angles to the diagram of Fig. 2;

Fig. 4 shows a further detail of the structure of Figs. 2 and 3;

Fig. 5 shows detail of starting mechanism for starting the A extensor mechanism under control of a received starting signal impulse;

Fig. 6 shows another view of the mechanism of Fig. 5;

Fig. 7 shows, in theoretical mechanical diagram, details of structure of a B extensor machine taken as an elevational view sectioned across the axis of the power shaft;

Fig. 8 shows further detail of the structure of Fig. 7 taken as an elevation at right angles to the view of Fig. 7;

Fig. 9 shows a detail of the view of Fig. 7;

Fig. 10 shows details of the mechanical structure of an A extensor machine in exploded perspective view;

Fig. 11 shows details of the mechanical structure of a B extensor machine in exploded perspective view;

Fig. 12 shows a sectional view of a B extensor machine;

Fig. 13 shows a detail of the structure of Fig. 10; and

Fig. 14 shows a detail of the structure of Fig. 7. Referring to Fig. 1, rectangles 11 and 12 represent A extensors, rectangles 13 and 14 represent B extensors, rectangles 15 and 16 represent substations, the substation 15 being connected to A extensor 11 by line conductor 17, the A extensor 11 being connected by cable 18 and local signal conductor 19 to a transmitting multiplex distributor 20 which is connected over a line conductor 21 to a receiving multiplex distributor 22, which is connected by cable 23 and local signal conductor 24 to B extensor machine 14, which is connected further by conductor 25 through windings 26 of magnets 27 and thence over line conductor 28 through substation 16 to ground connection. The elements here recited from 15, 17 to 28, and 16 have been mentioned in the order of transmission of communication from substation 15 to substation 16. A further conductor 29 connects B extensor 14 to A extensor 12 and current over this conductor prevents the arming of magnet 27 in extensor 12 from responding to signals transmitted through winding 26 of that magnet. Identical apparatus and circuits are shown for transmission of communication signals from substation 16 to substation 15 through A extensor 12, line conductor 31, B extensor 13, and through a magnet winding 32 of magnet 45 in A extensor 11 with similar provision of conductor 30 for echo suppression.

Structure of an A extensor machine

The A extensor machine represented in rectangle 11 is shown in theoretical mechanical detail in Figs. 2 to 6, inclusive, and in exploded perspective in Fig. 10. It comprises a power shaft 35 which rotates continuously by power received through gear 36 and which bears fixed thereupon the continuously moving parts of three clutches which drive intermittently three start-stop cam sleeve members; namely, a permutation code signal receiving cam sleeve, or "code cam sleeve" 37, a blocking cam sleeve 38, and a retransmission function cam sleeve 40.

Code cam sleeve 37 is driven by friction clutch 41, 42 under tension of spring 43 and is restrained in its stop position by stop arm 44 under control of code signal magnet 45, as illustrated in Figs. 5 and 6. Cam sleeve 37 bears five combinational cams 46 and an operating cam 47. Blocking cam sleeve 38 is driven by a friction clutch 50 whose power take-off member 51 has a spline projection 52 passing through a radial slot at the apex of a cam 53 on cam sleeve 38. The cam sleeve 38 and the take-off member 51 are restrained in stop position by a latch 54 which engages the spline projection 52 and is arranged to release the friction clutch 51 under control of cam 47 through operation of a train of members including 90, 92, 93, 94, and 95, as described in detail below. Cam sleeve 38 bears blocking cam 55, sixth impulse cam 56, and first transfer cam 57, in addition to the mentioned cam 53.

Retransmission function cam sleeve 40 is driven by a toothed clutch 59 whose power member 60 is pinned to shaft 35 and whose sliding take-off member 61 is splined to cam sleeve 40, is urged by spring 62, and is restrained from engagement with power member 60 by detent 63 under joint control of magnet 64 and of cam 55 on cam sleeve 38.

Sliding clutch member 61 bears crown cam 68,

while cam sleeve 40 bears second transfer cam 65, deleting cam 66, and resetting cam 67.

In Fig. 2, operating springs and retractile springs, other than clutch springs, are omitted to simplify the drawing.

The three clutches and cam sleeves are related as follows: Reception is initiated by release of the armature of the code signal magnet which starts the code cam sleeve, and just before the end of its rotation the code cam sleeve starts rotation of the blocking cam sleeve which, in its initial angle of rotation, withdraws a blocking latch and unlocks the armature of magnet 64 to respond to electromagnetic control. Retransmission is initiated by receipt of a controlling impulse in magnet 64 from a multiplex distributor, to start rotation of the retransmission cam sleeve.

With code signal magnet 45 energized, its armature 72, Figs. 3, 5, and 10, and armature carrier 82 are held attracted in counterclockwise position upon pivot 48. Its striker 73, shown as an adjustable screw, is held in its marking position. A rocking lever 74 engages and latches a rotary gate member 75, Figs. 5 and 10, which engages and restrains the stop arm 44 of code cam sleeve 37. Upon de-energization of magnet 45 in response to a received starting impulse of spacing nature, retractile spring 76 rotates armature carrier 82 upon its pivot 48, causing striker 73 to operate the sliding pin 77, which rocks a bell crank lever 78 clockwise upon its pivot 79, thereby rocking the lever 74 upon its pivot 80 against tension of compression spring 81, Fig. 6, to unlatch the rotary gate member 75. Armature lever 82 is restored to its operated position shown by a cam lobe 99, Fig. 10, on cam sleeve 37 in engagement with a cam follower 100 on armature lever 82.

In rotation of cam sleeve 37, five code cams 46 operate successively five code cam followers 83, Figs. 3 and 10, about a common pivot 84 against tension of individual springs 85, thus drawing five code swords 86 momentarily against a marking anvil 136 or spacing anvil 137 carried by an armature sublever 138, accordingly as armature lever 82 may be at the instant in its counterclockwise position in response to a received marking signal impulse or in its clockwise position in response to a received spacing signal impulse. Armature sublever 138 is operated by adjustable striker 148 on armature lever 82 against which it is drawn yieldably by spring 146. By engagement with marking or spacing anvil of armature sublever 138 to form a fulcrum, and by power received from code cam follower 83 through a socket articulation, the five code swords 86 are positioned in clockwise or counterclockwise position severally, and thereafter are pressed against one arm of five code T-levers 87 by individual springs 85, rotating the T-levers and shifting the five code slides 88. A sixth equipment comprising code sword, T-lever and code slide is described under "Break signal structure" later herein. A more complete description of the code signal responsive apparatus of Fig. 3 may be had from Patent No. 1,904,164 issued to S. Morton et al.

Bell crank cam follower 90 pivoted at 91, Figs. 2, 3, and 10, is positioned in the path of cam 47, Figs. 2 and 3, and operates momentarily just before cam sleeve 37 stops, to rock an arm 92 fixed to a rocking shaft 93, Figs. 2 and 10, to which is fixed an arm 94, which engages and rotates clockwise, a spring-urged trigger 95 pivoted at 96 which, when rotated clockwise by arm 94, re-

leases the clutch latch member 54. Retractile spring 87 rotates the member 54 on its pivot 88, drawing the member 54 out of the path of spline 52. A cam follower roller 88 is mounted upon member 54 and is positioned in the path of cam 53, Fig. 2. Engagement of cam 53 and its follower 88 rotates member 54 on its pivot to relatch the member 54 and trigger 95.

While the blocking cam sleeve 38 is in its position of rest, the apex of cam 55, Figs. 2, 4, and 10, holds cam follower 101 in blocking position upon its pivot 102, and a connecting spring 103 also holds the rocking member 104 in blocking position upon the common pivot 102 and in abutting engagement through mechanical contact 179 with follower 101, thus maintaining a blocking latch member 69 upon member 104 in position to engage an armature lever 70 carrying armature 71 of magnet 64 to prevent more than a negligible movement of armature 71. In any other angular position, apex 55 permits follower 101 and its associated members 104, 69 to rotate under tension of spring 106, which will position blocking latch 69 to clear the path of extension arm 70.

Sixth impulse cam 56 is positioned to operate its follower 110, Figs. 2 and 3, at an early instant in rotation of cam sleeve 38. Cam follower 110 is fixed to a rocking shaft 111 which carries also an operating arm 112 articulated by socket connection to sixth sword 113.

The apex of first transfer cam 57, Figs. 3 and 10, is positioned to restrain its follower 114 while cam sleeve 38 is at rest and to operate its follower 114 and jockey blade 89 into transfer locking position soon after operation of cam follower 110 when cam sleeve 38 has started. Follower 114 is pivoted at 115, Figs. 2 and 10, and has an operating arm 116, Figs. 2, 3, and 10, which carries a jockey blade 89 engaging locking projections of six storage slides 88. Operation of follower 114 by arrival of cam 57 at stopped position lifts the blade 89 from slides 88.

Armature lever 70 normally is held in its position shown in Figs. 4 and 10 by attraction of differential magnet 64 and is blocked against effective retractile operation by blocking latch 69. Armature lever 70 is fixed upon rocking shaft 117 upon which shaft the clutch detent 63 is rotatably carried. Detent 63 has an adjustable striker screw 118 in engagement with armature lever 70, the two members 63 and 70 being held in engagement by a spring 119. When armature 71 is in attracted position as shown, the distal end of detent 63 is in position to be engaged by crown cam 68 on sliding clutch member 61. When armature 71 has been released by de-energization of magnet 64, retractile spring 120 rotates the armature lever 71 and detent 63 to remove the end of detent 63 from crown cam 68, thereby releasing the sliding member 61 under tension of spring 62 to engage power member 60 to drive the cam sleeve 40.

The apex of cam 65 on cam sleeve 40 is positioned to operate its follower 121 soon after starting of rotation of transmission sleeve 40. Follower 121 is of yoke shape pivoted at 122 with an integral arm 123 which is connected through a link 124 to a pivoted arm 125 under tension of spring 126, Fig. 3, and rocking upon a fixed pivot 127. The distal end of arm 125 bears a stud 128 which constitutes a common pivot for six transfer members 130, each of which is connected through a ball and slot articulation to one of six individual bell crank levers 131 hav-

ing operating arms 132 which control the position of electrical contact springs 133. All levers 131 are pivoted upon a common fixed stud 134, and each is held in either of its two positions by an individual jockey 135.

The deleting cam 66 operates its follower 140 momentarily upon its pivot 141 near the end of rotation of cam sleeve 40. Pivoted upon the fixed pivot stud 134 is a yoke lever 142 bearing an integral bail blade 143 shaped to engage all of the six bell crank levers 131. Members 140 and 142 are articulated by an extension finger 144 on member 140 riding against an extension 147 of member 142.

The apex of resetting cam 67 on cam sleeve 40 operates its follower 145 at any median point in its rotation and the apex passes the follower before stopping, thus leaving the follower free to fall at any instant during the period of rest of the cam by reason of de-energization of magnet 64 and release by latch 69. Follower 145 is pinned to rocking shaft 117 to which armature lever 70 also is pinned, each operation of follower 145 thus returning lever 70 toward magnet 64, thereby drawing clutch detent 63 through spring 119 into position to be engaged by crown cam 68. By this movement of armature lever 70, the blocking end thereof is withdrawn from the path of blocking latch 69, permitting the latch 69 to move into blocking position.

Crown cam 68 on sliding member 61 of clutch 59 engages the end of detent 63 and the member 61 slides in response to that engagement, thus disengaging itself from power member 60, interrupting transfer of power from member 60 to member 61.

Referring to A extensor 11, Fig. 1, magnet 45 is held energized during periods of nontransmission by current through its windings 32, which are components of the extension line circuit including battery 151, resistor 152, retransmission contacts 153 of B extensor 13, closed contact 154, central station local conductor 155, windings 32 of code signal magnet 45 in A extensor 11, extension circuit line conductor 17 to substation 15, break key 156, transmitter contacts 157, slow-to-release break signal relay 158, recorder selector magnet 159, and ground. Differential magnet 64 is held energized during periods of nontransmission by current through its winding 160 which is included in a local circuit with battery 161, resistor 162, and ground. An operating circuit for differential magnet 64 includes battery 161, resistor 162, winding 163 of magnet 64, local central station conductor 19, segment 164, and brushes 165 of multiplex distributor 20 and ground.

Retransmitter 170 in A extensor 11, Fig. 1, includes six electrical contact springs 133, Figs. 1, 3, and 10, adjustable into marking position by six transfer members 130, Figs. 2, 3, and 10, and into spacing position by bail blade 143. Five contact springs 133 numbered 1 to 5 and shown in spacing position in Figs. 1, 3, and 10, are controllable through five cam followers 83, and one contact spring 133 No. 6, shown in marking position, Fig. 1, is controllable through cam 56, Fig. 2. Contact springs 133, Nos. 1 to 5, are connected through cable 18 to segments 1 to 5 of multiplex distributor 20. Marking transmission battery 172 is connected through resistor 173 to marking contacts 174, Nos. 1 to 5, and to spacing contact 175 of springs 133, No. 6, in the transmitter 170. Spacing transmission battery 176 is connected through resistor 177 to spacing contact of spring 75

133, No. 3, and to marking contact of spring 133, No. 6, and when contact spring 133, No. 6, is in marking position, as shown, the spacing battery connection is extended through a local conductor 178 to spacing contacts of springs 133, Nos. 1, 2, 4, and 5.

The maximum speed of operation of the transmitter at substation 15 is less than the speed of operation of distributor 20 at the central station.

Operation of the A extensor machine

Operation of the A extensor machine 11, Fig. 1, illustrated in detail in Figs. 2 to 6 inclusive and Fig. 10, is as follows: Upon receipt over line conductor 17, Fig. 1, of a starting spacing impulse of an incoming start-stop code signal, code signal magnet 45, Fig. 3, releases armature 72 which moves armature carrier 82 and striker 73, Figs. 3 and 5, to operate pin 77, Figs. 5 and 6, bell crank lever 78, and rocking lever 74 to unlatch gate 75 which releases stop arm 44 and permits a revolution of selector cam sleeve 37. The five cams 48 cooperate with the armature 72, armature lever 82 and armature sublever 138 of code signal magnet 45 to adjust the five swords 86 in code manner in response to the received permutation code signal. Cam 47 then operates the bell crank cam follower 90, and the cam sleeve 37 stops with the armature lever 82 in marking position.

Cam follower 90, rocked momentarily by cam 47, operates through elements 92, 93, 94 and 95 to unlatch the member 54 which is operated by its spring 97, Fig. 3, to release spline 52 of clutch 51, thus starting the cam sleeve 38. The first operation by cam sleeve 38 is effected through its cam 55, Figs. 4 and 10, which moves its apex away from its follower 101 pivoted at 102, and through spring 103 and mechanical contact extension 109 permits spring 106 to rock the member 104 upon pivot 102, thereby rocking the blocking member 69 away from the end of armature lever 70 and clearing a path for operation of lever 70, so that armature 71 may be operated by spring 120 when released by magnet 64. This condition maintains until cam sleeve 38 completes its rotation. The second operation by cam sleeve 38 is effected through its cam 56, Figs. 2 and 3, which operates momentarily its cam follower 110, Fig. 3, upon rocking rod 111 which has fixed upon it an arm 112 with socket articulation to a No. 6 sword 113, which by reason of the marking position of the armature 72 of selector magnet 45 at this time by "stop signal" or resting time current, results in setting sword 113 into marking position, as shown in Fig. 3. The third operation by the cam sleeve 38 is effected through its cam 57 which releases its cam follower 114 and rocks the member 114 upon its pivot rod 115, Fig. 2. Member 114 carries upon its arm 116 a jockey blade 89 which now holds in adjusted position the six signal storage slides 88. Locking the slides 88 permits overlap, a second code signal being stored in swords 86, after which lifting of the blade 89 will permit the slides 88 to respond to springs 85 acting through swords 86 and 113 and T-levers 87 to position the five slides 88 in accordance with the marking or spacing nature of the five impulses of the stored code signal and to position the sixth slide 88 into marking position in accordance with the marking condition of magnet 45 and its armature 72 at the instant of reoperation of cam 53 and cam follower 110. The received signal and the marking nature of the

stop signal also thus have been transferred to slides 88, and magnet 45 with its associated selector members is conditioned to receive a subsequent code signal in overlap manner.

The received code signal remains stored in the slides 88 pending receipt of a controlling signal from segment 164 of the multiplex distributor 20 to de-energize the magnet 64. Magnet 64 has two windings of which 160 has a continuous polarizing current sufficient to hold its armature attracted and sufficient to re-attract its armature after a small angular movement permitted by engagement of members 69 and 70, Fig. 4, after release of armature 71 when member 69 is in blocking position.

Release of armature 71 by magnet 64 is effected by a current in the second winding 163 of magnet 64 under control of the multiplex distributor over conductor 19, segment 164 and brush 165, the current received from the multiplex distributor being in reversed magnetic effect compared with the magnetic effect of the described polarizing current, so that the magnetism of magnet 64 is reduced or cancelled by receipt of the signal from the multiplex distributor, and armature 71 is released by reason of reduced or neutralized magnetism. Should the cam sleeve 38 be in stop position, holding the follower 101 and latch 69 in obstructing position, armature lever 70 will move slightly to engage the latch 69 and shortly thereafter will be re-attracted by magnet 64, when the signal from the multiplex distributor is terminated. This reverse method of operating an armature is suited to the conditions herein described because a quicker response of armature 71 is attained compared with its response to direct energization of magnet 64. Release of armature 71 permits its attached arm 70, Fig. 4, to move the detent 63 of sliding clutch member 61 so that cam sleeve 40 is started and is driven with ample power by its toothed connection to the motor shaft 35. The first operation by cam sleeve 40 is effected through cam 65, which engages and moves momentarily its follower 121 pivoted on rod 122 and having an arm 123 bearing a stud which operates a link 124 to carry pivot rod 128 and its six transfer members 130 into engagement with the six slides 88, thereby rocking the members 130 upon the rod 128 in code combinational manner and rocking the bell crank arms 131, Figs. 3 and 10, upon their common pivot rod 134, each such arm having a detent engaging an individual jockey 135 to retain the arm 131 in rocked position. A bell crank arm 132, upon each arm 131, controls an electrical contact member 133, and thus sets up an electrical storage corresponding to the mechanical storage in slides 88, so that the five combinational impulses are registered upon five electrical contact members 133 and are connected to multiplex distributor segments for transmission over a multiplex channel. The sixth condition is set up upon a sixth contact member 133, No. 6, Fig. 1, in response to the position of the No. 6 sword 113, Fig. 3.

The brushes of the multiplex distributor now transmit to the multiplex channel the signals set upon the five contact members 133, Nos. 1 to 5. During such transmission the cam 53 engages its follower roller 98 and restores the latch member 54. Cam sleeve 38 then reaches its stop position in which position cam 55 operates follower 101 extending the spring 103 and pressing the finger 69 against the end of armature lever 70.

Sleeve 40 then performs its second operation effective through cam 66, which engages and rocks its cam follower 140 momentarily. Member 140 is pivoted at 141 and bears a finger 144 projecting into engagement with a yoke lever 142 pivoted upon pivot rod 134, which is the common pivot rod of all arms 131. The momentary motion of member 140 is imparted to member 142 which carries a blade 143 common to arms Nos. 1 to 5 of the six signal arms 131. The blade 143 engages any arms 131, Nos. 1 to 5, which have been elevated by transfer members 130 and depresses all engaged arms into spacing position as shown in the drawings where all depressed arms 15 are retained by the individual jockey springs 135, so that the electrical storage of the code signal transiently effective upon contact members 133, Nos. 1 to 5, is deleted. Arm 131, No. 6, is not so restored, since the normal position of that arm 20 is marking position.

Cam sleeve 40, as a final controlling act effective through cam 67 and its cam follower 145, rocks the shaft 117 and restores armature 71 and its armature lever 70 into resting position, as shown in Fig. 4, permitting detent 69 to assume its locking position in the path of lever 70 and bringing the armature 71 near the poles of magnets 64 so that the polarizing magnetic energization of magnet 64 seizes and holds the armature 71, thus holding clutch detent 63 in position to be engaged by crown cam 68.

The last act of the cycle of the A extensor occurs when the crown cam 68 upon clutch member 61 engages detent 63, resulting in sliding the member 61 out of engagement with clutch member 60, thus stopping the rotation of member 61 and of cam sleeve 40. Jockey lever 182, urged by spring 181, presses its roller cam follower 183 into a notch in cam 184 on sleeve 40, operating to force sleeve 40 into its stop position and to prevent clutch 59 from grinding.

Structure of B extensor machine

Mechanical structure of a B extensor machine indicated in rectangles 13 and 14, Fig. 1, is illustrated in theoretical mechanical detail in Figs. 7, 8, 9, and 12, and in exploded perspective in Fig. 11. A power shaft 200 is rotated continuously by a motor (not shown) and bears fixed upon it the continuously rotating member 201 of a toothed clutch 202 of which the sliding member 203 drives a start-stop cam sleeve 204, the clutch being controlled through a crown cam 205 and cam follower 206 pivoted at 207. To the cam follower 206 is fixed the armature 208 of magnet 210.

Cam sleeve 204, Figs. 7 and 14, bears six cams 211, five of which are code combinational cams having individual bell crank followers 212 each controlling a combinational code contact pair 213 and each having a latch end 214 engageable by an individual one of five bell crank latches 215 mounted on a common pivot stud 216. A sixth bell crank follower 209, Fig. 14, mounted upon pivot stud 217 common to the five followers 212, is similar to followers 212 except that it has no latch end 214 nor latch 215, and it controls a stop impulse contact pair 218.

Cam sleeve 204 bears also a cam 219 having a follower 220 pivoted on stud 217 and controlling a contact pair 221. Also on cam sleeve 204 are twin cams 222 of three radial dimensions and a cam 223 controlling a follower 224 pivoted on common stud 217 and bearing a bail blade 225 which spans the five bell crank followers 212 of

the five code combinational cams 211 and of the five latches 215.

Upon the frame of the machine 226, Fig. 11, are mounted five code combinational signal impulse receiving magnets 230 each having individual armatures 231, sliding rods 232, pivoted latches 233, and signal impulse storage members 234. The five storage members 234 are pivotally mounted upon a common stud 235 and have individual operating arms 236 shaped to engage individually arms of the five bell crank latches 215.

The mentioned twin cams 222 have twin followers 239 formed as extension ends of a cam follower yoke 240 having both arms pivoted upon stud 217. Yoke 240 carries a bail blade 241 spanning the five operating arms 236. Spring 242, Fig. 7, urges the follower yoke 240 to hold its bail blade 241 against arms 236, but is weaker than any one of the five springs 243, so that any one of the springs 243 may rotate its associated member 234 to overcome the spring 242 and rotate the followers 239 into engagement with cams 222, in response to a received marking signal impulse.

Operating yoke 240, through an extension member 247, Fig. 12, engages lever 244 pivoted at 245 and controls the lever 244 through a spring 246 and an adjustable striker screw 248. An arm 249 of the lever 244 has its end positioned to block movement of cam follower 206, thus preventing magnet 210 from operating the member 206 and clutch 202, Fig. 8, unless at least one impulse storage member 234 is set to marking position, thereby setting bail blade 241 into its median position as will be described, and moving arm 249 of lever 244 out of the path of a lug 254 on cam follower 206.

Referring to Fig. 1, the B extensor 14 has its five magnets 230 connected in series with battery 250 and resistor 251 and through cable 23 to segments 1 to 5 of multiplex distributor 22. Segment 252, No. 6, of the distributor 22 is connected through local conductor 24 to magnet 210 in series with battery 253. A retransmission circuit extends from battery 255, resistor 256, code contact pairs 213, and start-stop contact pair 218, closed contactor pair 257, local conductor 25, windings 26 of magnet 27 in A extensor 12, extension line conductor 28 to substation 16 and through break key 258, contacts of transmitter 259, slow-to-release relay 260, and selector magnet 261 to ground return. A further circuit for echo suppression includes battery 262, resistor 263, windings 264 of magnet 27, local conductor 29, contact pair 221, and ground return.

Operation of B extensor machine

Brushes 265 in distributor 22 pass over segments 1 to 5, and magnets 230 are energized in combinational manner moving the associated triggers 233 and storing the marking signals in storage members 234. Storage members which have been operated in response to marking signal impulses move latches 215 to a mean position without effect and move bail blade 241 and yoke 240 to the effect that yoke 240 operates lever 244 and removes its blocking arm 249 from the path of extension 254 on cam follower 206.

Brushes 266 then engage segment 252, No. 6, and cause energization of magnet 210, which operates armature 208 and cam follower 206, to operate the clutch 202 and to start the cam sleeve 204.

Cam 219 permits its follower 220 to close its contact pair 221, thus energizing magnets 27 through winding 264 and rendering the magnets 27 unresponsive to signals in line conductor 28. 5 Cams 222 then present a minimum radius and permit followers 239 and bail blade 241 to release all operated storage arms 236 which individually operate corresponding latches 215 and release corresponding bell crank followers 212, where- 10 upon cams 222, by highest radius, operate yoke 240 and bail blade 241 to restore all operated storage members 234 into latched relation with the triggers 233. Yoke 240 also restores lever 244 and arm 249 and relocks cam follower 206. 15 At this time cam follower 209 and contacts 218 have transmitted a starting impulse. Cam followers 212 and contacts 213 now transmit code signal impulses over the line circuit including battery 255, resistor 256, code contact pairs 213, 20 local conductor 25, winding 26 of magnets 27, extension line conductor 28, and substation 16 to ground.

After transmission of the code signal impulses, cam follower 209 closes contact pair 218 for the 25 stop signal impulse and cam 219 operates its follower 220 to reopen contact pair 221.

Should brushes 265 not operate any magnet 230 by a received marking signal impulse, the ensuing impulse from segment 252 will energize magnet 30 210, but armature 208 will remain blocked by member 249, clutch 202 will not be operated, and a "blank" code combination received over the multiplex channel 21 will be suppressed and will not be retransmitted over the extension line 35 conductor 28.

Break signal structure

The break signal structure comprises in part several elements encountered above; namely, 40 break key 156 and slow-to-release relay 158 at substation 15, similar equipment 258, 260 at substation 16, Fig. 1, cam 56 and follower arm 110, rocking shaft 111, Figs. 2 and 3, operating arm 112, sword 113, T-lever 87, No. 6, storage slide 45 88 No. 6, transfer element 130 No. 6, bell crank lever 131 No. 6, contact member 133 No. 6, Figs. 1 and 3, local conductor 178, Fig. 1, and contact pairs 154 and 257, Fig. 1.

Additional structural elements pertaining to 50 the break signal system are illustrated in Figs. 7, 9, 11 and 12; namely, a cam 300 on cam sleeve 204, Figs. 7 and 11, having a follower 301 pivoted on common pivot stud 217 under tension of spring 302 and carrying upon a movable pivot 303 a driving pawl 304 and a rocking member 305 urged by a spring 306 against a stop lug 310 and having a detector bail blade 307, which is positioned to engage undercut lugs 308 formed on bell crank latches 215 Nos. 1, 2, 4, and 5, when in latching 55 position, as shown, and to engage lug 309, Fig. 9, on bell crank latch 215 No. 3, when that latch is in nonlatching position by control of its associated impulse storing member 234, 236, after receipt of a No. 3 signal impulse of marking nature. 60 Bail blade 307, when operated, will engage at least one of the five lugs 308 and 309, except that when latches 215 are set for the code combination, marking, marking, spacing, marking, marking, or "figures shift code signal," the bail blade 307 will pass under all lugs 308 and over the lug 309 without engaging any of the said lugs. Any other code signal may be chosen in place of the "figures shift code signal" here described for illustration. 65

70 Upon a stud 311, Figs. 7 and 12, is rotatably

mounted a cam member 312 having a cam apex 313, a stop pin 314, a series of ratchet teeth 315, and a retractile spring 316 urging the cam member and its stop pin 314 against a shoulder of a stop arm 318 pivoted upon the stud 311 and adjustable by a clamping member 319, which passes through a slot 320 in a frame member 317. Ratchet teeth 315 are engaged for propulsion by driving pawl 304 and are engaged for retention by detent pawl 322 pivoted at 323 under tension of spring 324 and having an extension 325 in the plane of the driving pawl 304. Attached to rocking member 305 is an operating arm 326 having an extension 327, which passes under the pawl 304.

Cam member 312, when operated in successive steps, causes its cam apex 313 to operate a bell crank cam follower 330 pivoted at 331 and having an operating contact pair 154 in Figs. 7 and 11, appearing in circuits as 154 in 13, Fig. 1, and 257 in 14, Fig. 1.

Break signal annunciators, which may be either of visible nature or audible, or both, are provided at 333 and 334 in substations 15 and 16, respectively, Fig. 1, under control of slow-to-release relays 158 and 260, respectively.

Break signal annunciators are provided also at 336, 331, 338, and 339 in the central offices, Fig. 1. Contacts 340, Fig. 13, in any A extensor machine are operated by lever 133 No. 6 and control an annunciator 336 or 338, Fig. 1. Contacts 341, Figs. 7 and 11, in any B extensor machine are operated by follower 330 and cam apex 313.

Break signal operation

Function of the break signal system is to operate a signal device 334 at substation 16, Fig. 1, in response to operation of break key 156 at substation 15. With cam member 312, Fig. 7, as shown, with relay 260, Fig. 1, adjusted for a delay of .2 second and with transmission at 390 operations per minute, the key 156 must be held open for one second to operate the signal device 334 and must be held open thereafter as long as continuous operation of the signal device is desired.

When key 156 is maintained open, magnet 45, Fig. 1, is de-energized and remains in de-energized condition, starting the cam sleeve 37, Figs. 2, 3, and 10, and maintaining it in continuous rotation, and in each such rotation adjusting all swords 86 and 113 to spacing position and setting all contact springs 133, Nos. 1 to 6, inclusive, to spacing position. At each rotation of multiplex distributor brush 167, transmission of a permutation code signal, namely: marking, marking, spacing, marking, marking, is effected from marking battery 172 to resistor 173, contact 175, contact spring 133 No. 6, now in spacing position, local conductor 178, contacts 133 Nos. 1, 2, 4, and 5, and cable 18 to multiplex segments 1, 2, 4, and 5, and from spacing battery 176 through resistor 177, contact and spring 133 No. 3, and cable 18 to multiplex segment No. 3.

Receipt of the described transmitted permutation code signal in the B extensor 14 results in tripping the triggers 233 Nos. 1, 2, 4, and 5, Fig. 7, and starting the cam sleeve 204. Cam 222 and cam follower 237 permit springs 243 and operating arms 236 to operate latches 215, Nos. 1, 2, 4, and 5, clearing all lugs 308 from the path of bail blade 307, and while follower arm 239 remains within the notch of cam 222, the cam 300 permits its follower 301 to rotate, causing the driving 75

pawl 304 to rotate the cam member 312 one step, where it is held by detent 322, after which cam follower 301 is retired by cam 300. Repeated reception of the described "figures shift code signal" advances the cam member 312 in repeated steps until pawl 304 engages the last ratchet tooth 315, and apex 313 operates its follower 330 to open the contacts 257 in 14, Fig. 1. Repeated transmission of "figures shift code signal" must continue further until, after .2 second, the relay 260 releases its armature, and the signal device 334 becomes energized and will continue energized as long as key 156 is maintained open.

Upon reclosure of key 156, a continuous marking signal is transmitted over extension line conductor 17, the signal in the multiplex channel responsively changes to marking nature for the remainder of the instant cycle of the A extensor. B extensor 14 therefore registers a code signal which may be for T, M, N, V or "letters shift," depending upon the number of impulse intervals of the instant cycle of the A extensor following the change from spacing to marking condition of the transmitter, and upon operation of cam follower 301, the bail blade 307 engages at least one lug 308 as a fulcrum, upon which fulcrum the rocking member 305 is rocked by power received through movable pivot 303 from spring 302. Rotation of member 305 lifts arm 326 and lug 327 and thereby lifts pawl 304 which in turn engages and lifts detent 322, releasing the cam member 312 which is returned by spring 316, releasing its cam follower 330 and reclosing contact pair 257 in 14, Fig. 1, thus reenergizing relay 260 and terminating energization of signal device 334.

Transmission of the break signal has been effected by a prolonged interval of spacing signal in the extension line conductors, during which a permutation code signal has been repeated several times in the multiplex channel. The prolonged spacing signal is not one of the thirty-two usable signal combinations of a start-stop permutation, differing as it does from the blank combination by including no rest or stop pulse. It is not one of the thirty-one usable combinations of a multiplex code, but corresponds to the idle condition of a multiplex channel, which is not a signaling condition. Thus, the break signal which traverses the extension lines belongs neither to the start-stop nor the multiplex code, and is therefore an ultra-code signal which produces, through the use of suitable translating devices, a repetition of a predetermined code signal of the communication code of signals in the multiplex channel.

A break signal originating on extension circuit 17 either by key 156 or by an accidental break in the line 17 will operate central office signal devices 336 and 337, while a break signal originating on extension circuit 28 either by key 258 or by an accidental break in the line 28 will operate central office signal devices 338 and 339. In each central office, signal device 336 or 338 identifies the home extension circuit as the location of the break, while signal device 337 or 339 identifies the remote extension circuit as the source of the signal.

It will be observed that the opening of key 156 or other interruption of line 17 results in the transmission of "figure shift code signals" to the receiving printer represented by selector magnet 261, until the number of cycles of the B extensor necessary to effect the opening of contacts 154 by ratchet cam 312 have been accomplished. The receiving printer at station 16 rep-

resented by selector magnet 261, will thus be placed out of correspondence with the home recorder at station 15, represented by selector magnet 159, if the printers had been operating previously in the "letters shift" condition. Compensation for this condition may be had in an operating routine according to which the operator at the message transmitting station, such as station 15, before sending any character printing signals, sends a signal for placing both printers in the desired "letters shift" or "figures shift" condition.

The placing of one recorder out of correspondence with the other, upon operation of the break signal key, may be obviated by providing that the code signal combination to be transmitted in the multiplex channel shall correspond to the instant case shift condition of the recorders, and therefore to the last transmitted case shift signal, instead of being a predetermined, invariable signal combination. A system for automatically generating either of two case shift signals according to which of those signals had been most recently transmitted, the system being readily adaptable to the apparatus of the present invention, is disclosed in copending application Serial No. 167,163 filed October 4, 1937, by L. M. Potts.

Specific extensor machines and specific circuits have been described in this specification to illustrate the invention, but other mechanical devices may embody the invention equally well and effect the desired results in satisfactory manner within the scope of the invention.

What is claimed is:

1. A method of transmitting a break signal in multiplex extension circuit operation which comprises transmitting a break signal in the form of a prolonged ultra-code signal, translating the ultra-code signal into a predetermined code signal of the code of communication code signals, and transmitting the selected code signal repeatedly.

2. A method of transmitting a break signal in a multiplex extension circuit system which comprises transmitting a break signal in the form of a repeated predetermined code signal of the code of communication signals, translating the repeated code signal into a prolonged signal of ultra-code nature, and transmitting the prolonged signal in an extension circuit of the system.

3. In a multiplex extension circuit system, a plurality of stations, a multiplex channel connecting two of said stations, an extension line connecting one of said two stations to a further one of said stations, means for transmitting a prolonged break signal over said extension line, and means responsive to receipt of said prolonged break signal for transmitting recurrently over said multiplex channel a predetermined code signal selected from the multiplex channel communication code of signals.

4. In a multiplex extension circuit system, a plurality of stations, a multiplex channel connecting two of said stations, an extension line connecting one of said two stations to a further one of said stations, means for transmitting recurrently over said multiplex channel a predetermined code signal selected from the multiplex channel communication code of signals, and means responsive to said recurrently transmitting means for transmitting a prolonged break signal over said extension line.

5. In a multiplex extension circuit system, a

plurality of stations, a multiplex channel connecting two of said stations, an extension line connecting one of said two stations to a further one of said plurality of stations, means for transmitting over said extension line permutation signal impulses of a predetermined communication code signal accompanied by an ultra-code signal impulse of predetermined nature, further means for transmitting over said extension line repeatedly and continuously the permutation signal impulses of said predetermined code signal accompanied by a further ultra-code signal impulse of other than said predetermined nature, and translation means responsive to said further ultra-code signal impulse to transmit repeatedly into said multiplex channel a different predetermined code signal.

6. In a multiplex extension circuit system, a plurality of stations, a multiplex channel connecting two of said stations, an extension line connecting one of said two stations to a further one of said plurality of stations, means for transmitting repeatedly over said multiplex channel a code signal constituting one of a code of communication code signals, counting means responsive to said code signal when repeated, and means controlled by said counting means and effective to transmit an ultra-code signal over said extension line.

7. In a multiplex extension circuit system, a plurality of stations, a multiplex channel connecting two of said stations, an extension line connecting one of said two stations to a further one of said plurality of stations, means for transmitting repeatedly over said multiplex channel a code signal constituting one of a code of communication code signals, rotary counting means responsive to said code signal when repeated, means controlled by said counting means and effective after a predetermined number of counts to transmit an ultra-code signal over said extension line, and adjustment means rotatable coaxially with said rotary counting means for altering the said number of counts.

8. In a multiplex extension circuit telegraph system, a multiplex channel, a counting member, electrical contacts controlled by said counting member when in a predetermined position reached through successive counting operations, means responsive to a predetermined code signal received over said multiplex channel and controlling said counting member to effect successive counting operations, a simplex extension line including said electrical contacts, and mechanism in said extension line responsive to control only by said electrical contacts.

9. In a start-stop receiving device, a plurality of permutation members, a first cam sleeve, means for starting said first cam sleeve into operation in response to a received signal, means operable selectively by said first cam sleeve to set predetermined ones of said members according to received signals, a second cam sleeve, means controlled by said first cam sleeve to start said second cam sleeve, and means operable by said second cam sleeve to set a further one of said members according to a received signal.

10. In a start-stop repeating device, a plurality of electrical retransmission members, a first cam sleeve, means for starting said first cam sleeve into operation in response to a received signal, means operable selectively by said first cam sleeve to set predetermined ones of said members according to received signals, a second cam sleeve, means controlled by said first cam sleeve to start

said second cam sleeve, and means operable by said second cam sleeve in response to a received signal to change the electrical condition of some of said electrical retransmission members.

11. In a multiplex extension circuit telegraph system, a central station, a multiplex transmission system terminating in said central station, a normally closed extension circuit terminating in said central station, first repeating means connected to said multiplex system and to said extension circuit responsive to a prolonged open condition of said extension circuit and effective to transmit a repeated predetermined code signal into said multiplex transmission system, second repeating means connected to said multiplex system and to said extension circuit responsive to a repeated predetermined code signal received from said multiplex transmission system and effective to transmit a prolonged open condition into said extension circuit, a first annunciator device connected to said first repeating means, operative when said first repeating means is responding to the prolonged open condition of the first-mentioned extension circuit, and a second annunciator device connected to said second repeating means, operative when said second repeating means is transmitting into the second-mentioned extension circuit a prolonged open condition.

12. In a multiplex extension circuit system, a start-stop extension line, a multiplex channel, storage means for receiving and storing a code signal from said multiplex channel, retransmitting means for retransmitting said stored code signal into said extension line under control of said storage means, starting means controlled periodically by said multiplex channel to start said retransmitting means, and wholly mechanical blocking means for preventing operation of said starting means and controlled by said storage means to unblock said starting means when a signal is stored in said storage means.

13. In a multiplex extension circuit system, a simplex extension line, a multiplex retransmitting channel, a multiplex receiving channel, a retransmission mechanism having a winding in said extension line to retransmit signals into said retransmitting multiplex channel, a receiving mechanism having windings in said receiving multiplex channel and having contacts responsive to signals in said multiplex receiving channel to retransmit signals into said extension line, echo contacts in said receiving mechanism, means for operating said echo contacts and for holding said echo contacts in operated condition while said receiving mechanism is transmitting, and a circuit including said echo contacts and a winding in said retransmission mechanism and effective to render said retransmission mechanism unresponsive to signals in said extension line.

14. In a multiplex extension circuit system, a start-stop extension line, a multiplex channel, means to receive from said start-stop channel and to store a code signal, retransmitting means to retransmit said stored signal to a multiplex channel, and means associated with said retransmitting means to reset said storing means to effect the deleting of a retransmitted code signal from said storing means.

15. In a multiplex extension circuit system, a start-stop extension line, a multiplex channel, first storage means, receiving means for receiving a code signal from said extension line and for storing the received signal in said first storage means, second storage means, transfer means

for transferring said stored code signal into said second storage means, retransmitting means for retransmitting said stored code signal into said multiplex channel under control of said second storage means, and blocking means controlled by said receiving means for blocking said retransmitting means and effective to unblock said retransmitting means responsively to receipt of each received code signal.

16. In a multiplex extension circuit system, a start-stop extension line, a multiplex channel, first storage means, receiving means for receiving a code signal from said multiplex channel and for storing the received signal in said first storage means, second storage means, transfer means for transferring said stored code signal into said second storage means, retransmitting means for retransmitting said stored code signal into said extension line under control of said second storage means, and blocking means controlled by said receiving means for blocking said retransmitting means and effective to unblock said retransmitting means responsively to receipt of each received code signal.

17. In a telegraph repeater, a start-stop receiver, a multiplex retransmitter, a constantly rotating shaft, a first cam member, first means responsive to a received signal to couple said first cam member to said shaft, a second cam member, second means controlled by said first cam member to couple said second cam member to said shaft, a third cam member, third means controlled by said retransmitter to couple said third cam member to said shaft, and further means controlled by said second cam member while in stop position to prevent operation of said third means.

18. In a telegraph repeater, a rotary member, means responsive to a received signal to start said rotary member, a retransmission control device, electromagnetic means to start said retransmission control device at regular periodic intervals, and means carried by said rotary member to render ineffective said electromagnetic means.

19. In a telegraph repeating system, means to register severally the impulses of a received code signal of a plurality of impulses, and means to retransmit for each registered code signal a corresponding code signal of a smaller plurality of impulses which impulses for some received code signals correspond to a series of impulses embodied in the received and registered code signal but which impulses for one predetermined received code signal vary from the series of impulses comprising the received and registered code signal.

20. In a multiplex extension circuit system, a start-stop extension line, a multiplex channel, storage means for receiving and storing a code signal from said multiplex channel, retransmitting means for retransmitting said stored code signal into said extension line under control of said storage means, electromechanical starting means controlled periodically by said multiplex channel to start said retransmitting means, and wholly mechanical means for blocking the mechanical portion of said starting means and controlled by said storage means to unblock the mechanical portion of said starting means when a signal is stored in said storage means.

21. In a multiplex extension circuit system, a start-stop extension line, a multiplex channel, storage means for receiving and storing a code signal from said multiplex channel, retransmit-

ting means for retransmitting said stored code signal into said extension line under control of said storage means, electromechanical starting means for said retransmitting means energizable periodically under control of said multiplex channel irrespective of the presence or absence of signals in said storage means, and wholly mechanical means for blocking the mechanical portion of said starting means and controlled by said storage means to unblock the mechanical portion of said starting means when a signal is stored in said storage means.

22. In a multiplex extension circuit system, a start-stop extension line, a multiplex channel, electromagnetic means for registering a code signal received from said multiplex channel, mechanical storage means controlled by said registering means for storing a code signal registered thereby, retransmitting means for retransmitting said stored code signal into said extension line under control of said storage means, electromechanical starting means for said retransmitting means energizable periodically under control of said multiplex channel irrespective of the presence or absence of signals in said storage means, and wholly mechanical means for blocking the mechanical portion of said starting means and controlled by said storage means to unblock the mechanical portion of said starting means when a signal is stored in said storage means.

23. In a multiplex extension circuit system, a multiplex system, a start-stop extension line, means to receive from said multiplex system and to store mechanically a code signal, retransmitting means to retransmit said stored signal to said start-stop extension line, and means associated with said retransmitting means and independent of any electrical signaling impulses in said multiplex system to reset said storing means to effect deleting of a retransmitted code signal from said storing means.

24. In a multiplex extension circuit system, a multiplex system, a start-stop extension line, means to receive from said multiplex system and to store mechanically a code signal, retransmitting means to retransmit said stored signal to said start-stop extension line, and means wholly controlled by said retransmitting means to reset said mechanical storing means.

25. In a multiplex extension circuit system, a multiplex system, a start-stop extension line, means to receive from said multiplex system and to store mechanically a code signal, retransmitting means to retransmit said stored signal to said start-stop extension line, and means wholly controlled mechanically by said retransmitting means to reset said mechanical storing means.

26. A method of transmitting a break signal in multiplex extension circuit operation which comprises transmitting a break signal in the form of a prolonged ultra-code signal, translating the ultra-code signal into a predetermined code signal of the code of communication code signals, transmitting the selected code signal repeatedly, translating the repeated code signal back into a prolonged signal of ultra-code nature, and transmitting the prolonged signal in an extension circuit of the system.

27. A method of transmitting a break signal in multiplex extension circuit operation which comprises transmitting in an extension circuit a break signal in the form of a prolonged ultra-code signal, translating the ultra-code signal into a predetermined code signal of the code of communication code signals, transmitting the se-

lected code signal repeatedly in a multiplex channel, translating the repeated code signal into a prolonged signal of ultra-code nature, and transmitting the resulting prolonged signal in another extension circuit.

28. A method of transmitting a break signal in multiplex extension circuit operation which comprises transmitting in an extension circuit a break signal in the form of a prolonged ultra-code signal, translating the ultra-code signal into a predetermined code signal of the code of communication code signals, transmitting the selected code signal repeatedly, translating the code signals in excess of a predetermined number into a prolonged signal of ultra-code nature, and transmitting the resulting prolonged signal in another extension circuit.

29. In a multiplex extension circuit system, a multiplex channel, an extension circuit, and a retransmitting device interconnecting said channel and said extension circuit, said retransmitting device including signal responsive means controlled by signals received from said multiplex channel, signal transmitting means for impressing signals upon said extension circuit, mechanical storage means interposed between said signal responsive means and said signal transmitting means having a storing position in which signals from the multiplex channel are stored in said storage means and a transferring position in which stored signals are transferred to said transmitting means, and means to retain said storage means in an intermediate position until said transmitting means is ready to receive a transferred signal.

30. In a multiplex extension circuit system, a start-stop extension line, a multiplex channel, first storage means, receiving means for receiving the code signal from said extension line and for storing the received signal in said first storage means, second storage means, transfer means for transferring said stored code signal into said second storage means, retransmitting means for retransmitting said stored code signal into said multiplex channel under control of said second storage means, and means controlled jointly by said receiving means and said multiplex channel for setting in operation said retransmitting means.

31. In a multiplex extension circuit system, a start-stop extension line, a multiplex channel, first storage means, receiving means for receiving the code signal from said extension line and for storing the received signal in said first storage means, second storage means, transfer means for transferring said stored code signal into said second storage means, retransmitting means for retransmitting said stored code signal into said multiplex channel under control of said second storage means, and means controlled primarily by said receiving means and secondarily by said multiplex channel for setting in operation said retransmitting means.

32. In a multiplex extension circuit system, a start-stop extension line, a multiplex channel, first storage means, receiving means for receiving the code signal from said extension line and for storing the received signal in said first storage means, second storage means, transfer means for transferring said stored code signal into said second storage means, retransmitting means for retransmitting said stored code signal into said multiplex channel under control of said second storage means, means controlled periodically by said multiplex channel and normally ineffective

for starting said retransmitting means, and means controlled by said receiving means for placing said retransmitting means under positive and sole control by said periodically controlled means.

33. In a multiplex extension circuit system, a start-stop extension line, a multiplex channel, electromagnetic means for registering a code signal received from said multiplex channel, first mechanical storage means controlled by said signal registering means, second mechanical storage means controlled by said first mechanical storage means, retransmitting means for retransmitting said stored code signal into said extension line under control of said second storage means, and means controlled by said retransmitting means for timing the setting of said second storage means under control of said first storage means.

34. In a multiplex extension circuit system, a start-stop extension line, a multiplex channel, electromagnetic means for registering a code signal received from said multiplex channel, first mechanical storage means controlled by said signal registering means, second mechanical storage means controlled by said first mechanical storage means, retransmitting means for retransmitting said stored code signal into said extension line under control of said second storage means, means controlled by said retransmitting means for timing the setting of said second storage means under control of said first storage means, and means actuated by said retransmitting means for resetting said first storage means.

35. In a multiplex extension circuit system, a multiplex channel, an extension circuit, and a retransmitting device interconnecting said channel and said extension circuit, said retransmitting device including signal responsive means individual to each impulse of a signal combination controlled by signals received from said multiplex channel, signal transmitting means for impressing signals upon said extension circuit, and mechanical storage means interposed between said signal responsive means and said signal transmitting means having normal, storing and transmitting positions.

36. In a multiplex extension circuit system, a multiplex channel, an extension circuit, and a retransmitting device interconnecting said channel and said extension circuit, said retransmitting device including signal responsive means individual to each impulse of a signal combination pressing signals upon said extension circuit, and controlled by signals received from said multiplex channel, signal transmitting means for im-

10 mechanical storage means interposed between said signal responsive means and said signal transmitting means having normal, conditioned and actuated positions.

37. In a telegraph system, an incoming line, an outgoing line, and means for repeating signals from said incoming to said outgoing line including a start-stop receiving distributor, a continuously operable transmitting distributor, means controlled by said receiving distributor for initially storing signals received from said incoming line, normally locked means for intermediately storing signals received from said initial storing means, means controlled by said receiving distributor for unlocking and relocking said intermediate storing means, means for impressing signals upon said transmitting distributor, and means controlled jointly by said receiving distributor and said transmitting distributor for controlling said last-mentioned means according to the signal storage condition of said intermediate storing means.

38. In a start-stop receiving device, a selector magnet, signal registering means conditioned by said magnet in accordance with received signals, a first cam sleeve to position said signal registering means into operative relation with respect to said magnet, means controlled by said magnet to place said first cam sleeve into operation in response to a received signal, a second

35 40 45 cam sleeve, means controlled by said first cam sleeve to place said second cam sleeve into operation, and means controlled by said second cam sleeve to position said signal registering means into operative relation with respect to said magnet.

LOUIS M. POTTS.
